UNITED STATES PATENT OFFICE.

KARL MÜLLER, OF NEW YORK, N. Y., ASSIGNOR TO NICHOLAS MÜLLER'S SONS, OF SAME PLACE.

DESIGN FOR A LAMP-BODY.

SPECIFICATION forming part of Design No. 16,964, dated October 26, 1886.

Application filed September 9, 1886. Serial No. 213,168. Term of patent 7 years.

To all whom it may concern:

Be it known that I, KARL MÜLLER, of the city, county, and State of New York, have invented a new and original Design for a Lamp-
5 Body, of which the following is a specification.

The nature of my design is shown in the accompanying photograph, to which reference is made.

10 The leading feature of my newly-designed lamp-body consists of the bowl and a ram's head, having legs behind the horns.

In the photograph, A is the ram's head. B is the snout of the same; C, the horns, forming handles; D, the cup, partly between the horns; 15 F, the ram's legs, in the same plane with the bottom of the snout, and which, with the bottom of the snout, form a triangle; G, figures in relief on the side of the bowl; H, the cover of the bowl.

Having thus described my design, I claim as 20 new and desire to secure by Letters Patent—

1. The design for a lamp-body, substantially as herein shown and described, consisting of a ram's head, a bowl on the ram's head and partly between the horns, and legs behind the head. 25

2. The design for a lamp-body, substantially as herein shown and described, consisting of a ram's head, the legs, and the bowl having ornate- 30 ments in relief on its outer surface.

In testimony that I claim the foregoing as 30 my invention I have signed my name in presence of two subscribing witnesses.

KARL MÜLLER.

Witnesses:

MARTIN PETRY,
SIDNEY MANN.
